INVENTOR

Benjamin F. Oler.

BY

John Street Jackson.

ATTORNEY.

UNITED STATES PATENT OFFICE.

BENJAMIN F. OLER, OF WOODBURY HEIGHTS, NEW JERSEY.

ADJUSTABLE RESISTANCE UNIT.

1,371,049.

Specification of Letters Patent. Patented Mar. 8, 1921.

Application filed September 28, 1918. Serial No. 256,054.

To all whom it may concern:

Be it known that I, BENJAMIN F. OLER, a citizen of the United States, residing at 4th and Elm streets, Woodbury Heights, in the county of Gloucester and State of New Jersey, have invented a certain new and useful Adjustable Resistance Unit, of which the following is a specification.

My invention relates to resistance units which are used in connection with electrical apparatus and are adjusted in position until an unknown required resistance is secured.

The purpose of my invention is to make the unit more compact at the same time that the short-circuiting contact is removed from possible injury and placed within the coil.

A further purpose is to provide a short-circuiting contact which will follow up the movement of the resistance wire due to expansion by reason of heat.

Further purposes relate to the structure of the unit and will appear in the specification and in the claims.

I have preferred to illustrate my invention by but one form, selecting therefor a form which is simple, inexpensive, compact and effective and which at the same time well illustrates the principles of my invention.

30 Figure 1 is a side elevation, showing my preferred form.

Figs. 2 and 4 are end elevations of the structure seen in Fig. 1.

Fig. 3 is a section of Fig. 2 on line 3—3.

35 Fig. 5 is a section of Fig. 3 upon line 5—5.

Fig. 6 is a diagrammatic view showing connections made.

In the drawings, similar numerals indicate like parts.

40 In the type of resistance unit to which my invention is applied, the unit must have a range covering the required resistance, but, except for convenience in preliminary setting of the adjustment, it is not necessary that the amount of the resistance used be known at any time.

45 In carrying out my invention, I wind the resistance wire 10 within the grooves 11 of an insulating core 12 of convenient spool form. The core may desirably be made of porcelain and the usual material for the winding is German silver. The variation in resistance is effected by cutting out coils of the wire by means of a short-circuiting rider contact. As far as outlined the construction is well known and quite generally used.

However, instead of applying the rider contact upon the outside of the spool winding, I slit the spool, as at 13, in order to provide for an interior contact. In order to avoid unduly weakening the spool, I prefer not to slit it the entire length, but unite the porcelain across both ends of the slit, as at 14. The spool is shown as conveniently open at one end at 15 and closed at 16 the other end at 16 for support of an adjusting screw.

The ends of the spool are beaded at 17 to provide for convenient attachment of contact heads 18 and 19 which are in good electrical contact with the wire and may be alike except for the size of openings 20 and 21 in them. They are retained in position by crimping the edges 22 about the beads. They may also protect and hold the ends 75 of the wire. These contact ends may be made of any reasonably good conductor and are conveniently formed of phosphor bronze.

The spool is mounted upon brackets 23, 80 24 which are nearly alike.

Their openings 20', 21' are different and bracket 23 is flattened at the top at 25 and apertured at 26 for coöperation with a spring washer. The brackets are notched at 27, in the usual manner to fit over binding posts.

Within the spool 12 is mounted an adjusting screw 28 which is turned by a knurled and slotted head 29 and is held from longitudinal movement by the closed end of the 90 spool. The reduced portion 30 of the screw is passed through the hole in the spool, so that the shoulder engages one side of the head and a washer 31, the other side thereof. The washer is held in position by a pin 32. 95 At the opposite end the shaft 33 of the screw fits within the openings of the head and standard and is supported by them.

In order that the screw may have good electrical contact with the standard 23, a 100 spring strip 34 is provided, which is effective as a washer and is retained against rotation with the screw by the projections 35 and 36 engaging with the flattened top of the standard and fitting in the opening 26 105 thereof respectively. The hole 20² provides for passage of the screw through the strip. The screw makes contact chiefly with the washer. The standards and heads may be engaged electrically to advantage by solder 110 or any other convenient means.

It will thus be seen that the head 17 is

in good electrical contact with one end of the resistance wire, but is insulated from the end of the screw; also that the head 16 is in good electrical contact with the opposite end of the wire and with the screw.

The short-circuiting contact with the wire is secured by a nut 37 advanced and retracted by screw rotation and a preferably spiral spring contact finger 38 carried by the 10 nut and turned at 39 to extend outwardly through the recess or slot 13 into engagement with the interior of the wire. The projection is outwardly spring-pressed in order that it may make good contact with the wire 15 and follow up the wire as the latter expands, by reason of the heat therein. At the same time it engages with the sides of the slot 13 to prevent rotation of the nut.

In operation, the unit is placed within 20 the circuit by means of the usual binding posts and the knurled head is turned to bring the flat and preferably slightly curved end 40 of the spring 38 into engagement with that particular part of the wire desired, 25 short-circuiting the coils lying between it and the left hand end of the resistance wire in Fig. 1, the adjustment being continued until suitable balance has been secured.

In order to clearly disclose one form of 30 practising my invention as required, I have described the construction shown in great detail, but without any intention of limiting myself to this construction further than may be required by limitation of the scope of the 35 claims through the prior art. This is particularly true because I know that there are many ways in which the construction may differ from that described, some of which I have myself designed.

40 Having thus described my invention, what I claim as new and desire to secure by Letters Patent is:—

1. A resistance unit comprising a longitudinally slotted insulating spool having 45 beaded ends, a resistance wire wound thereon, electrically conducting spool ends turned over the beads and making contact with the wire at the two ends, connections for the ends and an adjustable contact device en-

gaging the wire and electrically connected 50 with one of the ends of the wire to short circuit a part of the wire.

2. In a resistance unit, an insulating spool having beads on the end, a wire wrapped upon the spool, heads on the ends of the 55 spool turned over the beads and engaging and protecting the ends of the wire, a screw within the spool fixed against longitudinal movement by engagement with one end of the spool and electrically connected with one 60 of the heads and a contact device carried by the screw and adapted to engage with the wire to short-circuit part of the wire.

3. In a resistance unit, a longitudinally slotted insulating spool having an insulating head therein, a screw mounted therein and held against longitudinal movement by the insulating head, electrically conducting heads for the two ends of the spool, one supporting the screw and the other insulated from it, an electrically conducting nut on said screw and an electrically-conducting spring contact spiraled about the screw, retaining the nut against rotation and engaging the resistance wire through the slot. 75

4. A resistance unit comprising a longitudinally slotted spool, a resistance wire wound thereon, electrically - conducting heads secured to the spool and electrically connecting with the ends of the wire, electrically-conducting standards supporting the spool and connecting it with the circuit with which the unit is to be used, a screw within the spool secured against longitudinal movement at one end thereof, a spring contact 80 device between the other end of the screw and its standard and means upon the spring contact device to prevent it from rotating with respect to the standard.

5. In a resistance unit, a longitudinally 90 slotted spool, a wire wound thereon, connections for the wire, a screw within the spool connected with one end of the wire, a nut upon the screw and a spring contact spiraled about the screw connected with the nut to prevent 95 rotation thereof and engaging the wire through the slot.

BENJAMIN F. OLER.
